UNITED STATES PATENT OFFICE.

EDWIN C. HEATHCOTE, OF BROOKLYN, NEW YORK.

DESIGN FOR AN EMBLEM, PIN, BUTTON, OR SIMILAR ARTICLE.

59,590.

Specification for Design.

Patented Nov. 8, 1921.

Application filed June 3, 1919. Serial No. 301,575. Term of patent 7 years.

To all whom it may concern:

Be it known that I, EDWIN C. HEATHCOTE, a citizen of the United States, residing at the city of New York, borough of Brooklyn, Kings county, in the State of New York, have invented a new, original, and ornamental Design for an Emblem, Pin, Button, or Similar Article, of which the following is a specification, reference being had to the accompanying drawing, forming part thereof. In said drawing the figure is a face view

of an emblem, pin, button, or similar article, embodying or incorporating my said design.

I claim:

The ornamental design for an emblem, pin, button, or similar article, as shown.

EDWIN C. HEATHCOTE.

Witnesses:

CONRAD A. DIETERICH,
WILLIAM P. JONES.
